US00D839900S

(12) **United States Design Patent** (10) Patent No.: **US D839,900 S**
 Gan (45) Date of Patent: ** Feb. 5, 2019

(54) **DISPLAY SCREEN WITH GRAPHICAL USER INTERFACE**

(71) Applicant: **Shenzhen Valuelink E-Commerce Co., Ltd.**, Shenzhen (CN)

(72) Inventor: **Qing-Cao Gan**, Shenzhen (CN)

(73) Assignee: **Shenzhen Valuelink E-Commerce Co., Ltd.**, Shenzhen (CN)

(**) Term: **15 Years**

(21) Appl. No.: **29/624,894**

(22) Filed: **Nov. 6, 2017**

(51) LOC (11) Cl. **14-04**

(52) U.S. Cl.

USPC **D14/486**; D14/489

(58) **Field of Classification Search**

USPC D14/485-495

(57) **CLAIM**

The ornamental design for a display screen with graphical user interface, as shown and described.

DESCRIPTION

The FIGURE is a front view of a display screen with graphical user interface showing the claimed design. The broken line showing of the display screen is included for the purpose of illustrating portions of the article and forms no part of the claimed design. The broken lines depicting portions of the graphical user interface form no part of the claimed design.

1 Claim, 1 Drawing Sheet
